UNITED STATES PATENT OFFICE.

HENRY L. MEADE, OF NEW YORK, N. Y., ASSIGNOR TO WESTERN ELECTRIC COMPANY,
INCORPORATED, OF NEW YORK, N. Y., A CORPORATION OF NEW YORK.

TELEPHONE-EXCHANGE SYSTEM.

1,416,226.

Specification of Letters Patent. Patented May 16, 1922.

Application filed July 14, 1920. Serial No. 396,133.

To all whom it may concern:

Be it known that I, HENRY L. MEADE, a citizen of the United States, residing at New York, in the county of New York, State 5 of New York, have invented certain new and useful Improvements in Telephone-Exchange Systems, of which the following is a full, clear, concise, and exact description.

This invention relates to telephone exchange systems and more particularly to systems in which a number of subscribers may be connected together for common conversation with each other and a calling subscriber.

15 It frequently happens that an executive in charge of a department in a business organization may desire to convey by telephone to each of his assistants some information of common interest. In such cases it is 20 advantageous to establish quickly a common connection between the executive's telephone and all of the telephones of his assistants, thereby avoiding the loss of time and inconvenience which would result from establishing an individual connection with each 25 assistant.

It is the object of this invention to provide an improved system of this character, which will be inexpensive and simple to 30 operate, and which will permit any individual telephone of the system to be placed in common connection with a group of associated telephones, as well as in separate connection with any other individual telephone.

35 To attain this object in accordance with one feature of the invention a circuit arrangement is provided so that a common connection with a group of telephone lines may be established in exactly the same routine manner as an individual connection 40 with a particular telephone line. Another feature of this invention resides in a circuit arrangement by which any individual telephone in the associated group may be placed 45 in common connection with all of the remaining telephones of the group.

In accordance with still another feature, an arrangement is employed whereby it is 50 possible to place separate groups of associated telephones in common connection.

These and other features not specifically

mentioned will clearly appear from the following specification and the accompanying drawing, in which the figure shows one embodiment of the invention as applied to a 55 common battery telephone system having cut-off line jacks. Subscribers' lines are shown terminating on jacks 1 and 2, with which is associated a grouping jack 7. By the insertion of a plug 26 of a link circuit 60 C into jack 1, the operator may connect a subscriber at station 12 to a subscriber at station 13, or by inserting the plug into jack 7, may establish a common connection with the subscriber at station 13 and another subscriber 65 whose line terminates at jack 2. The link circuit C may be of any well known type, the station apparatus therefor being omitted since it is unessential to a proper understanding of the invention.

70 It is thought that the invention will be more fully comprehended by the following description of the operation of the system illustrated by the drawing. Assuming that the subscriber at station 12 desires an individual connection with the subscriber at station 13, whose telephone line terminates at jack 1, the removal of his receiver from the hook will operate the line relay 30 over an obvious circuit, thereby causing the illumination of the lamp 31. The operator will then insert plug 32 of the link circuit C into jack 33, disconnecting the line relay 30 at the tip and ring contacts of the jack. Lamp 31 will be extinguished on the release of 80 relay 30. The supervisory relay 35 operates over a circuit including the apparatus at station 12 so that lamp 36 is shunted by resistance 37 to prevent its illumination by current flowing through resistance 38 and 85 the sleeve contacts of plug 32 and jack 33. The operator, after operating listening key 27 and having ascertained that telephonic connection is desired with the subscriber at station 13, will insert plug 26 of link circuit 90 C into jack 1. This will cause a disconnection of conductors 17 and 19 from conductors 28 and 29 at the tip and ring contacts of the jack respectively. The operator will 95 now actuate the ringing key 10, to apply a source of ringing current 16 to the ring strand of the link circuit C and ground to

70

75

80

85

90

95

the tip strand. Ringing current will accordingly be sent over conductors 28 and 29, operating the bell of the telephone of the station 13. When the operator inserted plug 5 26 into jack 1, the supervisory lamp 9 was illuminated over the following path: from grounded battery through lamp 9, resistance 15, sleeve contacts of plug 26 and jack 1 to ground. When the subscriber at station 13, 10 in response to the calling signal, removes his receiver from the hook, and the ringing key 10 has been released, a circuit path is completed as follows: from grounded battery through the winding of supervisory relay 15 11, lower normal contact of ringing key 10, ring contacts of plug 26 and jack 1, conductor 29, telephone apparatus at station 13, conductor 28, tip contacts of jack 1 and plug 26 upper normal contact of key 10, to 20 ground. Supervisory relay 11 is accordingly actuated and shunts the lamp 9 by a resistance 14, thereby extinguishing it. The subscribers at stations 12 and 13 are now free to converse over an obvious circuit path 25 which is similar to that ordinarily used for common battery systems. On completion of the conversation the subscriber at station 13 will restore his receiver to the hook, thereby opening the circuit through the supervisory relay 11, to remove the shunt 14 from lamp 9, again causing its illumination. Similarly when the subscriber at station 12 restores his receiver, the supervisory lamp 36 will glow due to the release of relay 35. The operator 30 will now restore all apparatus to normal by removing plugs 32 and 26 from jacks 33 and 1 respectively.

Assuming now that the subscriber at station 12 desires a simultaneous connection 40 with the subscribers whose lines terminate at jacks 1 and 2, he will remove his receiver from the hook and signal the operator in control of the link circuit C. The operator, being informed that a common connection is 45 desired with subscriber at station 13 whose line terminates on jack 1, and with the subscriber whose line terminates on jack 2, will insert the plug 26 of link circuit C into grouping jack 7, which is associated with the 50 subscribers' line jacks 1 and 2. The station apparatus for the line terminating on jack 2 has not been shown in order to simplify the drawing. However, any usual arrangement such as shown for station 13 may be 55 used. The jack 7 may be associated with other lines, not shown, but which may be connected in a similar manner. Relay 6 is operated over the following circuit: from grounded battery, through lamp 9, resistance 15, sleeve contacts of plug 26 and jack 7, and winding of relay 6 to ground. Conductor 18 is disconnected at the right-hand normal contact of relay 6 from grounded battery, and connected at the middle alternate contact of such relay to the ring con-

tact of jack 7. Conductor 17 is disconnected from ground at the left-hand normal contact of relay 6, and connected to the tip contact of jack 7 at the left-hand alternate contact of such relay. Relay 5 operates over an 70 obvious circuit and connects conductor 18 to conductors 19 and 20 by means of its right-hand and middle alternate contacts, respectively. The operator then actuates ringing key 10 completing a circuit from the 75 source of signaling current 16, through the lower alternate contact of key 10, the ring contacts of plug 26 and jack 7, the middle alternate contact of relay 6, the common conductor 18, thence in parallel through 80 right-hand and middle alternate contacts of relay 5, the conductors 19 and 20, the normally closed ring contacts of jacks 1 and 2, the associated conductors of the line circuits such as conductor 29, the ringers at the substation of the line circuits such as at station 85 13, the other conductor of each line circuit, such as conductor 28, and the normally closed tip contacts of the jacks 1 and 2 to the common conductor 17 and thereafter 90 through the left-hand contact of relay 6, the tip contacts of jack 7 and plug 26 and the upper alternate contact of key 10 to ground. The current in this circuit will operate the usual ringers of the station on 95 the lines terminating at jacks 1 and 2, and of the stations on any other lines which may be associated with jack 7.

When relay 5 operated, connecting conductor 18 to conductor 19, the windings of the 100 line relays 3 and 4, associated with jacks 2 and 1, respectively, were short-circuited over obvious circuit paths through the middle and right-hand alternate contacts of relay 5. This short-circuiting of the line relay 105 windings provides low resistance paths for the ringing and battery currents and avoids the operation of such relays and the lighting of the line lamps 40 and 8, to give false signals. The subscribers will remove their 110 receivers, thereby establishing telephonic connection with the calling subscriber at station 12. For the subscriber's station 13, a circuit path may be traced as follows: from grounded battery through the winding 115 of supervisory relay 11, lower normal contact of key 10, ring contacts of plug 26 and jack 7, middle alternate contact of relay 6, common conductor 18, right-hand contact of relay 5, conductor 19, normal ring contact of 120 jack 1, conductor 29, through the telephone set at station 13, conductor 28, normal tip contact of jack 1, common conductor 17, left-hand alternate contact of relay 6, tip contacts of jack 7 and plug 26, and upper 125 normal contact of key 10 to ground. Relay 11 will be operated, extinguishing lamp 9 by shunting it with resistance 14. The other subscribers' stations associated with jack 7 will be connected in circuit in a similar man- 130

ner through other contacts of relay 5 and the normal contacts of their individual jacks. It will now be evident that each called subscriber is free to converse with the calling subscriber and with each of the other called subscribers. Upon the completion of the conversation, each subscriber, on replacing his receiver on the switchhook, will discontinue the supply of current from the cord 5 circuit through the apparatus at his station, and when all of the associated subscribers have finally replaced their receivers, supervisory relay 11 will be released, and lamp 9 10 will be lighted in the same manner as previously described in connection with the establishment of an individual connection. Upon observing the disconnect signal, the operator will withdraw the plug 26 from jack 7, causing the release of relay 6 and 15 consequently the release of relay 5, thereby restoring all apparatus to normal.

It is evident that the system possesses flexibility in that a variable number of jacks to which subscribers' lines are connected may 20 be connected in association for common talking and ringing. For instance, another jack may be connected to conductors 21 and 22 and one terminal of the corresponding line relay to conductor 25 in the same way as 25 shown for jacks 1 and 2. For each additional jack in the group there must be added to relay 5 an additional contact which would be associated with conductors such as 23 and 24 connected to conductor 18. Independently of the grouping jack 7, each associated subscriber may signal the operator 30 and obtain connection with any subscriber not in the associated group, with any other subscriber in the group, or with all other 35 subscribers of the group for common conversation.

To establish a connection with any non-associated station such as 12, the subscriber at station 13 will remove the receiver from 40 the hook and thereby actuate the line relay 4 over the following path: from grounded battery, through the right-hand normal contact of relay 6, common conductor 18, winding of relay 4, normal ring contact of jack 1, 45 conductor 29, telephone set at station 13, conductor 28, normal tip contact of jack 1, common conductor 17, left-hand normal contact of relay 6 to ground. The lamp 8 will then be illuminated over an obvious circuit. The 50 operator will then insert into jack 1 plug 32 of the answering end of the link circuit C. This will cause the normally closed tip and ring contacts of jack 1 to open, disconnecting conductors 19 and 17, releasing line 55 relay 4 and extinguishing lamp 8. The lamp 36 will be prevented from lighting by the shunt established therearound due to the operation of relay 35. The connection with the subscriber at station 12 will then be 60 completed by the insertion of plug 26 into

jack 33, which will similarly cause the disconnection of line relay 30. Upon completion of the conversation, supervisory lamps 9 and 36 will be lighted by release of the relays 11 and 35, respectively. 70

If the subscriber at station 13 desires connection with the associated subscriber's line connected at jack 2, the plug 32 will be inserted into jack 1, and the plug 26 into jack 2. The tip and ring contacts at each 75 jack will then open, disconnecting conductors 17, 19 and 20. This will permit conversation to be held through the link circuit over an obvious circuit path, independently of all associated apparatus. On the completion of the conversation, the supervisory lamps will be lighted in the usual manner, and upon withdrawal of the plugs from jacks 1 and 2, all apparatus will be restored 80 to normal. 85

If the subscriber at station 13 desires a common connection with all other associated subscribers served by the grouping jack 7, he will signal the operator in the usual way by removing his receiver from the hook, 90 causing the lighting of the line lamp 8. The operator will insert plug 32 into jack 1, and on ascertaining that a common connection is desired, will insert plug 26 into jack 7 which will establish a telephonic 95 connection of subscriber at station 13 through the link circuit C to the other associated subscribers in exactly the same manner as connection was established between the subscriber at station 12 and the associated subscribers, as explained in detail 100 above. In this case, however, the subscriber at station 13 will converse with the other associated subscribers through the link circuit C, because the insertion of the answering plug into jack 1 disconnects conductors 105 28 and 29 from conductors 17 and 19.

Another method of using this system is to establish a common telephonic connection between two groups of associated subscribers 110 interconnected, as shown on the drawing, the individual subscribers being provided with jacks, as jacks 1 and 2 of the group, and with a grouping jack, as jack 7. If the subscriber at station 13 should desire a common connection with the other subscribers of his own group, and a common connection with all of the subscribers of another group, he would inform the operator of this fact. She would then insert plug 26 into the 115 grouping jack of the called group of associated subscribers, and would then remove the answering plug 32 from jack 1, into which it was inserted in response to the signal of subscriber 13 and then insert it 120 into the grouping jack 7, having previously requested the subscriber at station 13 to hang up his receiver until called. Each end of the link circuit C is now plugged into a 125 respective grouping jack such as jack 7. 130

The operator will then ring on both ends of the link circuit by means of ringing keys 10 and 39 and all the associated subscribers of each group will be simultaneously called, 5 and upon removing their receivers from the switchhooks, a common conversational path will be established.

In a similar manner it is possible for any 10 group subscriber to converse with all others of his own group in common with one subscriber of another group or to converse with all the subscribers of another group.

The foregoing description illustrates one 15 method by which a calling subscriber may obtain a common connection with a number of associated subscribers. It is evident, however, that the particular arrangement shown may be departed from in various 20 ways and still be within the scope of this invention. Other variations in circuit arrangements will be readily obvious to those skilled in the art.

What is claimed is:

1. In a telephone exchange system, a 25 group of associated subscribers' lines, a terminal jack for each subscriber's line, a grouping jack associated with all of the lines of the associated subscribers, a cord circuit for connecting any two jacks, and means 30 for establishing through the grouping jack a common conversational connection between any one of the associated subscribers' lines and the remaining subscribers' lines in said group.
- 35 2. In a telephone exchange system, a plurality of individual subscribers' lines terminating at a central office, a group of associated subscribers' lines, means for establishing a conversational connection between 40 any one of said plurality of subscribers' lines and said group of associated subscribers' lines, a line lamp at the central office connected to each associated subscriber's line, and means for automatically disabling said 45 line lamp previous to the establishing of said conversational connection.
3. In a telephone exchange system, a plurality of individual subscribers' lines, a group of associated subscribers' lines, a terminal jack for each subscriber's line, a grouping jack associated with all of the lines of the associated subscribers' lines, a cord circuit for connecting any two jacks, means for establishing through the grouping jack 50 a common conversational connection between one of said plurality of individual subscribers' lines and the group of associated subscribers' lines, individual line signaling means connected to the line of each associated subscriber's line, and means for disabling said individual line signaling means responsive to the connection of the cord circuit with the grouping jack.
- 55 4. In a telephone exchange system, a group of associated subscribers' lines, a terminal 60 jack for each subscriber's line, a grouping jack associated with all of the lines of the

70 jack for each subscriber's line, a grouping jack associated with all of the associated subscribers' lines, a cord circuit for connecting any two jacks, means for establishing through the grouping jack a common conversational connection between any one of the associated subscribers' lines and the remaining subscribers' lines in said group, individual line signaling means connected to each of the associated subscribers' lines, and 75 means for disabling said individual line signaling means responsive to the connection of the cord circuit with the grouping jack.

5. In a telephone exchange system, a plurality of individual subscribers' lines, a 80 group of associated subscribers' lines, a terminal jack for each subscriber's line, a grouping jack associated with all of the lines of the associated subscribers' lines, a cord circuit for connecting any two jacks, means for establishing through the grouping jack a common conversational connection between 85 one of said plurality of individual subscribers' lines and the group of associated subscribers' lines, a source of potential for 90 the line circuit of the associated subscribers' lines normally connected thereto, and means for disconnecting said source responsive to the connection of the cord circuit with the grouping jack.

6. In a telephone exchange system, a group of associated subscribers' lines, a terminal jack for each subscriber's line, a grouping jack associated with all of the lines of the associated subscribers, a cord circuit for connecting any two jacks, means for establishing through the grouping jack a common conversational connection between any one 100 of the associated subscribers' lines and the remaining subscribers' lines in said group, a source of potential for the line circuits of the associated subscribers' lines normally connected thereto, and means for disconnecting said source responsive to the connection of the cord circuit with the grouping jack. 105

7. In a telephone exchange system, a plurality of individual subscribers' lines, a group of associated subscribers' lines, a terminal jack for each subscriber's line, a grouping jack associated with all of the associated subscribers' lines, a cord circuit for connecting any two jacks, means for establishing through the grouping jack a common conversational connection between one of 110 said plurality of individual subscribers' lines and the group of associated subscribers' lines, individual line signaling means connected to each line of the group, and means for shunting said individual line signaling means responsive to the connection of the cord circuit with the grouping jack. 115

8. In a telephone exchange system, a group of associated subscribers' lines, a terminal jack for each subscriber's line, a grouping jack associated with all of the lines of the 120

125

130

group, a cord circuit for connecting any two jacks, means for establishing through the grouping jack a common conversational connection between any one of the lines of the group and the remaining lines in said group, individual line signaling means connected to the line of each line of the group, and

means for shunting said individual line signaling means responsive to the connection of the cord circuit with the grouping jack. 10

In witness whereof, I hereunto subscribe my name this 1st day of July, A. D., 1920.

HENRY L. MEADE.
